FIG. 2

FIG. 3

FIG. 1

FIG. 4

FIGURE 1 is an elevational view of a drinking cup showing our new design;

FIGURE 2 is a top plan view;

FIGURE 3 is a sectional view taken along the line 3—3 of FIGURE 1; and

FIGURE 4 is a sectional view taken along the line 4—4 of FIGURE 1.

The characteristic feature of our design lies in a sidewall construction having upper and lower straight wall frustoconical portions separated by a compound arcuate section wherein the lower part of said section flares outwardly and smoothly into the upper part which has a small radius toroidal shape and merges tangentially into the lower part of the upper frustoconical portion.

We claim:

The ornamental design for drinking cup, substantially as shown and described.
